UNITED STATES PATENT OFFICE

146,198

DESIGN FOR A DISPLAY STAND FOR WALL AND FLOOR COVERINGS OR THE LIKE

Charles Eugene Stephenson, New York, N. Y., as-
signor to Congoleum-Nairn Inc., a corporation
of New York

Application July 3, 1945, Serial No. 120,482

Term of patent 14 years

(Cl. D80—11)

To all whom it may concern:

Be it known that I, Charles Eugene Stephenson, a citizen of the United States, residing in New York, in the county of New York and State of New York, have invented a new, original, and ornamental Design for a Display Stand for Wall and Floor Coverings or the like, of which the following is a specification, reference being had to the accompanying drawing, forming a part thereof, in which

Figure 1 is a front view of the display stand for wall and floor coverings or the like, showing my new design, all of the display panels being in raised position;

Figure 2 is a front perspective view thereof, with two of the display panels in lowered position for display of wall coverings, floor coverings or the like;

Figure 3 is a sectional elevation thereof taken on the line 3—3 of Figure 2, and

Figure 4 is a sectional elevation thereof taken on the line 4—4 of Figure 2.

The rear and end, not shown, are plain.

I claim:

The ornamental design for display stand for wall and floor coverings or the like, substantially as shown and described.

CHARLES EUGENE STEPHENSON.
